ADVERTISING DEVICES

Edouard Dechar, East Norwich, N.Y., assignor to
Dechar Corporation, Brooklyn, N.Y., a corpora-
tion of New York
Filed May 6, 1963, Ser. No. 278,111
5 Claims. (Cl. 40—77)

This invention relates to advertising devices.

An object of the present invention is to provide an advertising device especially suitable for suspending above a display area to keep the latter vacant and therefore fully available for merchandise, and which has advertising indicia on its outer surface that is illuminated in a relatively simple and improved manner for providing a visual effect which is highly effective in attracting and holding the attention of the observer and prospective customer.

Another object is to provide an advertising device having advertising indicia on its sides and bottom which are illuminated continuously and in succession to enhance the visual effect of the device.

A further object is generally to provide an advertising device of relatively simple construction and which is provided with improved means for attracting the attention of the observer and prospective customer.

The above and other objects, features and advantages of the invention will be more clearly understood from the following description of the invention considered in connection with the accompanying drawing of an illustrative embodiment of the invention in which:

FIG. 1 is a top plan view of an advertising device in accordance with the invention;

FIG. 2 is a side elevational view of the device with a portion cut away for the purpose of illustration;

FIG. 3 is a vertical sectional view, on a larger scale, taken on line 3—3 of FIG. 1;

FIG. 4 is a horizontal cross section with a portion cut away for purposes of illustration, taken on line 4—4 of FIG. 3; and

FIG. 5 is a vertical sectional view of the lower part of a device according to a modification.

Referring now to the drawing in detail, the display 10 comprises an enclosure 12 having a transparent cylindrical annular wall 14, preferably made of a suitable plastic sheet material. The bottom of the annular wall is closed by a transparent bottom wall 16, also preferably made of a suitable plastic sheet material as wall 14. The top of the annular wall is covered by a cover 18 which may be a flat circular wooden disc and preferably the bottom marginal edge portion of the cover is provided with a circular groove 20 into which the upper end of the annular wall fits. The cover is secured to said annular wall upper end by circumferentially spaced wood screws 22. The undersurface of the cover is covered by a sheet 24 of light reflective material.

A series of vertical suspension rods 26 are screwed into the top of the cover and extend upwardly therefrom for securing of the advertising device to the overhead, above the floor, which is then fully available for display of merchandise. The chamber 28 defined by enclosure 12 is illuminated by an electric light 30 which is suspended from the undersurface of the cover by bracket 34, and positioned centrally in the enclosure, is a suitably geared synchronous motor 36. The wires 38a and 38b for the light and motor, respectively, pass through the aperture 40 (FIG. 1) of the cover for connection to a suitable source of current.

The motor is operable to rotate a rotary hollow member 42. The rotary member comprises a centrally positioned rotary shaft 44 which has an axial passage 46

2

at its upper end into which extends the drive shaft 48 of motor 36. The shaft is held in position by a set screw 50 whereby member 42 is suspended for rotation below light 30.

5 A pair of upper and lower circular wire hoops 52 and 54, respectively, are secured to shaft 44, in vertically spaced relation, by a series of circumferentially spaced, radially extending, U-shaped wires 56 whose cross-members 58 are brazed to shaft 44 and whose arms 60 are suitably brazed at their ends to the hoops. An endless translucent sheet member 62 is suitably connected to the hoops to form an annular translucent wall for rotary member 42 and, similarly, the bottom of the rotary member is covered with a translucent sheet member 64 suitably secured to bottom hoop 54 to form the bottom wall of the rotary member. The walls of the rotary member may be made of suitable translucent plastic sheet material. It is to be noted that the rotary member is open at its top and that wall 62 is positioned adjacent and close to wall 14 and concentric therewith, while wall 64 is positioned adjacent and close to wall 16.

Walls 14 and 16 of the enclosure are each provided with advertising indicia 66. More particularly, the advertising indicia of wall 14, as best illustrated by FIG. 2, includes an upper band 68 of lettering and a lower band 70 of lettering, the latter comprising upper and lower lines 72 and 74, respectively, of lettering. Band 68 of lettering is formed by coating the desired inner surface of wall 14 with a layer of translucent material, for example, a translucent paint, ink or lacquer of a suitable color, such as white, and the opposite outer surface of the wall is stenciled with suitable lettering in a contrasting color, such as gold, and which may be an opaque material, as paint, ink or lacquer. The lines 72 and 74 of lettering of the lower band 70 are formed by stenciling an opaque paint, ink or lacquer 76, which may be colored black, to the inner surface of wall 14, below band 68, so that the coating outlines the desired lettering which may be seen through due to the transparency of the wall. Of course, while the bands have been described as including advertising indicia in the form of lettering, it will be understood that it is within the scope of the invention to provide other forms of advertising indicia in lieu of lettering or in addition thereto, for example, figures, designs, etc.

Bottom wall 16 of the enclosure is provided with concentric rows of transparent lettering 78 and 80 (FIG. 4) in a similar manner as lettering 72 and 74 is provided on wall 14. Obviously, wall 16 may be provided with transparent indicia other than lettering.

Translucent wall 62 of rotary member 42 has a height which is approximately the same as the height of band 70 of wall 14 and is in registry with the band. The inner surface of wall 62 is covered with upper and lower bands 82 and 84, respectively, of coatings of suitable translucent material, for example, a suitable paint, ink or lacquer. Upper band 82 is positioned in registry with upper line 72 of lettering and lower band 84 is positioned in registry with lower line 74 of lettering. Each band 82 and 84 is divided into two or more sections, designated 86 and 88 for the upper band, and 86a and 88a for the lower band and, in the case where two sections are provided, it is to be noted that sections 86 and 86a are displaced 180° with respect to each other and, similarly, sections 88 and 88a are displaced 180° with respect to each other. The different sections are formed by differently colored translucent coatings. For example, sections 86 and 86a can be colored black, section 88 red and section 88a blue, although it will be understood that various other color and color combinations can be provided. The differently colored sections

form separating vertical lines 90 on wall 62 which are diametrically opposed to each other.

The bottom wall 64 of rotary member 42 is similarly provided with concentric rows 92 and 94 (FIG. 4) of differently colored translucent sections in registry with rows of lettering 78 and 80. As herein illustrated, row 92 is provided with four sections 92a, 92b, 92c and 92d, of different colors and row 94 is similarly provided with differently colored sections 94a, 94b, 94c and 94d. Lines 96a, 96b, 96c and 96d define the end boundaries of the colored sections. The remaining outer and inner areas 97a and 97b, respectively, are also preferably colored with translucent paint, ink or lacquer.

As member 42 rotates during the operation of the device, the rows 72, 74, 78 and 80 of lettering are alternately illuminated by differently colored light due to the alternate positioning of the differently colored sections 86, 86a, 88, 88a, 92a, 92b, 92c, 92d, 94a, 94b, 94c and 94d behind the respective lettering. Moreover, each of the letters of each row of lettering is illuminated in succession as each line 90, 96a, 96b, 96c and 96d moves successively past the letter, to provide a striking visual effect for attracting the attention of the observer.

In accordance with another feature of the invention, the bottom edge of annular wall 14 of enclosure 12 may be provided with a downwardly extending skirt portion 98 having an inwardly extending flange 100 for supporting a series of inwardly facing mirrors 102 extending along the lower marginal edge portion of the enclosure. The mirrors reflect the visual effect occurring on the bottom of the device to further enhance its interest to the observer as he looks upwardly toward the device.

In accordance with still a further feature of the invention as best illustrated by FIG. 5, bottom wall 16 of the enclosure may be lowered to provide a space 104 which may be provided with a plurality of freely movable light-reflecting members or chips 106. Agitating means 108, secured to shaft 44, extends into the members 106 and moves them as member 42 rotates to further enhance the visual effect provided at the bottom of the device. The agitating means can comprise a series of radial rods or arms 108, circumferentially spaced around shaft 44 and secured to the latter. It is to be noted that the upper surface of the bottom wall 16 of the enclosure supports the reflecting chips.

This application is related to my copending application Serial No. 249,187, filed January 3, 1963, now abandoned.

While I have shown and described the preferred embodiment of my invention, it will be understood that the invention may be embodied otherwise than as herein specifically illustrated or described, and that certain changes in the form and arrangement of parts and in the specific manner of practicing the invention may be made without departing from the underlying ideas or principle of this invention within the scope of the appended claims.

I claim:

1. An advertising device comprising, an enclosure having a top wall, a side wall and a bottom wall, said side wall being provided with transparent indicia, a movable member positioned within said enclosure and having a side wall positioned adjacent said side wall of said enclosure, said side wall of said member having differently colored parts, light means positioned within said enclosure, means for moving said member so that said differently colored parts are successively moved past said indicia of said side wall of said enclosure for successive color illumination of the latter, a plurality of movable color reflecting members positioned on said bottom wall of said enclosure in covering relation therewith, and movable agitating means positioned for agitating said reflecting members concurrently with the movement of said movable member.

2. An advertising device comprising, an enclosure having a top wall, a side wall and a bottom wall, said side wall being provided with transparent indicia, a movable

member positioned within said enclosure and having a side wall positioned adjacent said side wall of said enclosure, said side wall of said member having differently colored parts, light means positioned within said enclosure, means for moving said member so that said differently colored parts are successively moved past said indicia of said side wall of said enclosure for successive color illumination of the latter, a plurality of movable color reflecting members positioned on said bottom wall of said enclosure in covering relation therewith, movable agitating means positioned for agitating said reflecting members concurrently with the movement of said movable member, and reflecting means positioned at the bottom of said enclosure and extending along the periphery thereof.

3. An advertising device comprising, an enclosure having a top wall, a side wall and a bottom wall, said side wall being provided with transparent indicia, a movable member positioned within said enclosure and having a side wall positioned adjacent said side wall of said enclosure, said side wall of said member having differently colored parts, light means positioned within said enclosure, means for moving said member so that said differently colored parts are successively moved past said indicia of said side wall of said enclosure for successive color illumination of the latter, a plurality of movable color reflecting members positioned on said bottom wall of said enclosure in covering relation therewith, movable agitating means positioned for agitating said reflecting members concurrently with the movement of said movable member, reflecting means positioned at the bottom of said enclosure and extending along the periphery thereof, and means connected to said enclosure for suspending the latter.

4. An advertising device comprising, an enclosure having a top wall, a cylindrical annular wall and a bottom wall, said annular wall and said bottom wall each being provided with transparent indicia, a rotary hollow member positioned within said enclosure below said top wall thereof and having an open top, a cylindrical annular wall of translucent sheet material positioned adjacent said annular wall of said enclosure and concentric therewith, and a bottom wall of translucent sheet material positioned adjacent and above said bottom wall of said enclosure, said annular wall and bottom wall of said rotary member each having differently colored parts, light means suspended from said top wall of said enclosure above said open top of said rotary member, motor means suspended from said top wall of said enclosure and operatively connected to said rotary member for moving said differently colored parts of each of said annular wall and bottom wall of said member, in succession, past corresponding parts of said transparent indicia of each of said annular wall and bottom wall of said enclosure for successive color illumination of each of said indicia, a plurality of movable reflecting members positioned on said bottom wall of said enclosure in covering relation therewith and below said bottom wall of said rotary member, agitating means connected to said rotary member for movement therewith and positioned for agitating said reflecting members during said movement, and means connected to said top wall of said enclosure for suspending the latter.

5. An advertising device comprising, an enclosure having a top wall, a cylindrical annular wall and a bottom wall, said annular wall and said bottom wall each being provided with transparent indicia, a rotary hollow member positioned within said enclosure below said top wall thereof and having an open top, a cylindrical annular wall of translucent sheet material positioned adjacent said annular wall of said enclosure and concentric therewith, and a bottom wall of translucent sheet material positioned adjacent and above said bottom wall of said enclosure, said annular wall and bottom wall of said rotary member each having differently colored parts, light

means suspended from said top wall of said enclosure above said open top of said rotary member, motor means suspended from said top wall of said enclosure and operatively connected to said rotary member for moving said differently colored parts of each of said annular wall and bottom wall of said member, in succession, past corresponding parts of said transparent indicia of each of said annular wall and bottom wall of said enclosure for successive color illumination of each of said indicia, a plurality of movable reflecting members positioned on said bottom wall of said enclosure in covering relation therewith and below said bottom wall of said rotary member, agitating means connected to said rotary member for movement therewith and positioned for agitating said reflecting members during said movement, reflecting means positioned at the bottom of said enclosure and

extending along the periphery thereof, and means connected to said top wall of said enclosure for suspending the latter.
